SLIDER FOR SEPARABLE FASTENERS

John Giovanni Scave, Long Island City, N. Y.,
assignor to Waldes Koh-I-Noor, Inc., Long
Island City, N. Y., a corporation of New York

Application March 22, 1938, Serial No. 197,345

6 Claims. (CL 24—205)

This invention relates to sliders for separable fasteners of the slide operated type and has for its principal object to provide means for locking the slider against movement on the fastener in any position of its travel without injury to or excessive wear of the parts of which such fastener is constituted.

Separable fasteners of the type above indicated are well known and usually comprise a pair of stringers having rows of interlocking elements attached along the opposed edges thereof and a slider embracing both rows of elements and movable along such rows for interlocking or disengaging the elements. The fastener structure may include covering means for the elements, such as, fabric or rubber, which coverings overlie the elements and extend from the root or attached portions of the elements out to approximately the outer projecting ends of the elements so that when the rows of elements have been interlocked by the slider, the outer edges of the covering strips meet and thereby hide the elements from view. In such fastener constructions the slider, which usually comprises a pair of spaced plates, also embraces the element covering strips. Movement of the slider on the fastener is usually accomplished by manual operation of a finger tab which is pivotally attached to a projection provided on one plate of the slider, usually the outer one, and such tab is sometimes provided with locking pins or fingers which when the tab is moved into a substantially horizontal position, enter a recess provided in the outer plate of the slider and engage with the interlocking elements positioned between the spaced plates of the slider. This type of slider lock has always been constructed on the theory that it must function as a positive bar to the movement of the elements through the slider and its effectiveness depended upon the locking pin or finger being so disposed on the slider and of such length that it could be inserted into the space between adjacent interlocking elements and when so positioned extend sufficiently into the path of such elements so as to effectively prevent movement of the slider with respect to such elements. While such a construction may be satisfactory for those separable fasteners in which the elements thereof are not concealed by covering material, it has not been at all satisfactory for separable fasteners in which the elements are covered because the locking pin must necessarily penetrate the covering material in order to function properly and after a while such material becomes

frayed and broken thereby giving the fastener an unsightly appearance.

According to this invention the finger or pull tab of the slider is provided with one or more cams or lugs which are adapted to extend through a recess provided in the top plate of the slider and engage the upper surfaces only of the elements or in the case where the slide fastener is covered, to engage those portions of the covering material which overlie the elements positioned beneath the lugs in their locked condition. The lugs are made wider than the width of the spaces between the interlocking elements so that they cannot be inserted therebetween but only effect a camming action on such elements. Co-operating with each lug provided on the pull tab, is an interior recess provided in the bottom plate of the slider, into which, the interlocking elements engaged by the lugs are forced and one end at least of which is formed to provide a distinct shoulder which functions as a stop to prevent longitudinal movement of the interlocking elements through the slider.

The advantages of this locking means as well as the novel details of construction thereof will become more apparent after a perusal of the following description taken in connection with the accompanying drawings in which Fig. 1 is a plan view of a covered fastener structure provided with a slider having a lock made in accordance with this invention, the pull tab being shown in locked position; Figs. 2 and 3 are sections taken along the lines 2—2 and 3—3, respectively, of Fig. 1; Fig. 4 is a side view of the slider shown in Fig. 1; Fig. 5 is a section taken along the line 5—5 of Fig. 4 to show the recesses in the bottom plate more clearly while Fig. 6 is a section taken along the line 6—6 of Fig. 4 to illustrate the relative positions of the camming lugs and recesses in the locked position of the former; Fig. 7 is a plan view of a modified form of the slider shown in Fig. 1; Fig. 8 is a view similar to Fig. 5 of the slider illustrated in Fig. 7 and Fig. 9 is a section taken along the line 9—9 of Fig. 7.

Referring more particularly to Figs. 1 to 3 of the drawings, the numeral 10 designates the slider which controls the locking and interlocking of the rows of elements 11 and 12, the individual elements of which are attached in staggered relation to the stringers 13 and 14, respectively, and are covered by the fabric covering strips 15, the latter of which preferably form part of the fabric material of which the stringers 13 and 14 are constituted. Actuation of slider

10 is accomplished by manual operation of the pull tab 16 which has its lower end pivoted at 17 to the lug 18 provided on the upper or outer plate 19 of the slider. In the drawings, the pull tab is shown in the position it should be while the slider is at rest, but when the slider is to be actuated such tab is raised about its pivot in order to facilitate the movement of the slider. During the sliding movement of the slider the rows of elements 11 and 12 and the covering strips 15 which overlie the upper surfaces of such elements enter into the channels formed between the spaced plates 19 and 20 of the slider. As is clearly shown in the drawings, the pair of channels 21 and 22 at the upper portion of the slider are angularly disposed to one another and converge into a single channel 23 disposed adjacently below the apex of the wedge-shaped section 24, the converging channels 21 and 22 feeding the rows of elements into proper relation to be interlocked when they reach channel 23 as the slider is moved upwardly or to the right, as viewed in Fig. 1 and the wedge-shaped section 24 forcing the interlocked elements apart into 25 disengaged condition when the slider is moved in the opposite direction or downwardly.

The pull tab 16 is provided at its lower or pivoted end with a pair of spaced locking lugs 25 which are arranged thereon so that they enter 30 and extend through the openings 26 provided in the top plate 19 of the slider when the pull is moved to the position shown in Figs. 1 to 3. As can be seen from Figs. 2 and 3, the spaced lugs 25, which are positioned at substantially right 35 angles to the pull tab 16, have their attached ends or root portions disposed in line with the pivotal axis of the pull tab 16 but extend outwardly from such pivotal axis at an angle greater than the angle between the tab and a plane 40 passed through such pivotal axis at right angles to the length of the tab, so that the outer ends of such lugs project beyond the lower end of the tab 16. The openings 26 are disposed laterally from the central longitudinal line of the slider 45 and extend lengthwise of the slider on each side of the lug 18 such openings being preferably just sufficiently long to provide no hindrance to the lugs 25 throughout their range of movement. Disposed beneath the openings 26 are a pair of 50 longitudinally extending recesses 27 formed out of the material of which the bottom plate 20 of the slider is constituted and disposed side by side in spaced relation intermediate the side flanges of such bottom plate and the central longitudinal portion thereof as is shown more clearly in Fig. 5. The recesses 27 each consist of a substantially vertical end shoulder 28 extending transversely to the path of travel of the elements in the rows and an inclined bottom surface 29 55 which extends upwardly from the bottom of the shoulder 28 towards the rear or lower end of the slider to the interior surface of the bottom plate 20 of the slider, as is shown more clearly in Figs. 2 to 4. Due to this form of the recesses it 60 is evident that the recesses will not interfere with the free movement of the fastener elements through the slider when the latter is moved upwardly or to the right, as viewed in Fig. 2, while when the slider is moved in the opposite direction, the attaching ends of the fastener elements 65 which pass over the recesses will be prevented from coming into engagement with the shoulders 28 of the recesses by the supporting fabric material of the stringers to which the attaching ends 70 of such elements are secured and the longitudinal

central portion 40 of the bottom plate 20 over which pass the interlocking ends of such elements, compare Figs. 1 and 5.

It will be apparent from the foregoing, however, that after the slider has been operated and the pull tab forced down by the operator to a substantially horizontal position, as is shown in the drawings, the locking lugs 25 will enter the recesses 26 and bear down against the strips of material covering the interlocking elements 10 thereby forcing the attaching ends of the elements disposed therebeneath by a camming action into the recesses 27. As the interlocking ends of the fastener elements overlie the longitudinal central portion 40 of the bottom plate 20 15 which functions as a stop against inward movement of such ends by the locking lugs 25, the camming action of the locking lugs upon the attaching ends of the elements will not disturb the normal alignment of such interlocking ends 20 of the elements as are acted upon with the interlocking ends of the other elements of the rows but will cause the attaching ends of the elements disposed above such recesses to pivot or rock inwardly about their interlocking ends, whereby the 25 attaching ends of the elements affected are forced into interlocking engagement with such recesses without materially disturbing the effective locking position of the interlocking ends of such elements in the rows. The portions of the locking 30 lugs 25 which engage with the covering portion of the separable fastener have a width greater than the width between the individual locking elements so that such lugs cannot enter into the spaces between the elements but exert their whole 35 force in a downward direction to cam the attaching ends of the interlocking elements into the recesses 27. The length of each of the recesses is approximately equal to the width of two of the elements plus the width of the space therebetween so that at least two of the elements may 40 be contained in such recess at the same time. In the locking of the elements in the recesses 27, the forcing of the pull tab 16 down into horizontal position will have the effect of moving the 45 slider slightly in the direction in which the tab is being pivoted so that an element in at least one of the rows will be forced into approximate engagement with the shoulder 28 of one of the recesses and in this position of such element the 50 locking lug positioned immediately above will be disposed directly upon the upper surface of the element thereby forcing such element into locked position against the bottom of the recess and the shoulder 28 and causing the pull tab to be 55 tilted slightly about its axis so that the elements disposed beneath the locking lug on the other side of the tab 16 will be placed under an increased pressure. The outer end portions of the locking lugs 25 are rounded to facilitate the camming action of such lugs and to reduce the possibility of wear on the covering strips 15 and due to the fact that such portions are slightly offset from the pivotal axis of the pull tab 16, the latter 60 will be locked in horizontal position until positively moved from such position preparatory to moving the slider along the rows of interlocking elements. This arrangement of the parts also 65 causes the slider to be moved in the opposite or forward direction when the pull tab is lifted, to 70 withdraw that shoulder 28 of the slider whose face is in locking engagement with the attaching end of an interlocking element thereby placing the parts in a condition for ready operation of the slider with free movement of the elements 75

therethrough. As has been indicated above the shoulders 28 of the recesses 27 are positioned so as to be substantially below the outer end portions of the locking lugs 25 when the locking tab is disposed in a horizontal position and slightly in back of the wedge-shaped section 24.

It will be appreciated from the foregoing that the slider locking means of this invention will successfully accomplish the purposes for which it was intended because in its operation it does not penetrate the covering material of the separable fastener to place a positive bar between the interlocking elements but locks the slider in position on the elements through a transversely directed camming force applied in such manner that the covering material overlying the elements will be in no way injured or subjected to such excessive wear that it will break down or become unsightly through usage.

20 Instead of positioning the camming lugs 25 and the forward vertically disposed shoulders 28 of the recesses 27 in line with each other, as is illustrated in Figs. 1 to 6, the camming lugs 25 on the pull tab 16 may be staggered so that each of such lugs will assume the same relation with respect to the interlocking elements in the row with which it cooperates when the pull tab 16 is forced into its horizontal locking position and the shoulders 28 may also be staggered so that an element 25 in each of the rows will be forced into engagement with such shoulders in the locked condition of the slider. These modifications in the arrangements of the camming lugs and the recesses are shown in Figs. 7 to 9 which also illustrate 30 the combined locking effect which is attained by staggering both the camming lugs and the recesses. In the construction illustrated in these figures, the camming lug 31 is disposed with respect to the pull tab 32 so that in the locked 35 position of the latter it is spaced farther from the wedge-shaped section 33 than is the camming lug 34. The recess 35 in the lower plate of the slider is staggered with respect to the recess 36 so that when the tab is disposed in horizontal 40 position the outer portions of the camming lugs 31 and 34 will be disposed almost directly above the forward vertical shoulders of such recess and each cooperating lug and recess will be capable of locking and interlocking elements in one of 45 the rows against the vertical shoulder of the recess, as shown for example in Fig. 2 of the drawings. In this construction it is preferable that the camming lugs be disposed with respect to the pivotal axis of the pull tab so that when the latter is in horizontal position, their effective forces 50 will tend to maintain the pull tab in locked position until the tab is manually released by the operator. In addition to the above described modifications it will also be understood that the recesses which are illustrated as being of such width 55 so that the portions of the fastener elements in back of the interlocking portions thereof only engage in such recesses, may be made sufficiently wider to accommodate the whole of an interlocking element and in the form illustrated in Fig. 5 may be formed as one recess without any intermediate raised portion therebetween.

It is evident that other changes in the construction and form of the slider may be made 70 without departing from the spirit of the invention or from the scope of the following claims.

I claim:

1. A slider for a separable fastener having rows of rigid fastener elements attached at their inner ends to the opposed edges of a pair of stringers

stringers and adapted at their outer ends to interlock in interfingered relation, comprising a top and a bottom plate secured together, said top plate having an opening extending therethrough laterally from the central longitudinal line of the slider, a member pivotally connected to said top plate and having a lug adapted to enter the said opening and to press the attached end of an element disposed beneath said opening, said bottom plate having a depression beneath said lug terminating in an end wall in the path of the attached end of an element depressed by said lug and a relatively elevated central longitudinal portion beneath the interlocking ends of the elements, said central longitudinal portion serving as a bearing on which the elements are rocked as their attached ends are depressed by said lug into the depression, whereby the interlocking ends of the elements are relatively undisturbed from their normal interlocking alignment while the attached ends of the elements depressed into the depression are prevented from moving by the said end wall of the depression.

2. A slider such as is defined in claim 1, in which the lug is wider at its element engaging end than the width of the spaces between adjacent fastener elements in the rows and the depression has an inclined bottom surface rising from the lower edge of the said end wall thereof towards an end of the slider.

3. A slider such as is defined in claim 1, in which said top and bottom plates have formed therebetween a Y-shaped passage for guiding the fastener elements into and out of interlocked engagement and said end wall of the depression is positioned adjacently to the juncture of the diverging arms of such channel, the bottom surface of the depression being inclined upwardly from the lower edge of said end wall towards the outer end of the central leg of such channel.

4. A slider such as is defined in claim 1, in which said top and bottom plates have formed therebetween a Y-shaped passage for guiding the fastener elements into and out of interlocked engagement and said end wall of the depression is positioned adjacently to the juncture of the diverging arms of such channel and said lug is attached to said pivotal member substantially in line with the pivotal axis of the latter and extends outwardly therefrom to form an obtuse angle therebetween, said lug being adapted to move the slider relative to the fastener elements in the direction in which said member is pivoted to bring the depressed attached end of the element engaged thereby into closer relation with said end wall.

5. A slider for a separable fastener having rows of rigid fastener elements attached at their inner ends to the opposed edges of a pair of stringers and adapted at their outer ends to interlock in interfingered relation, comprising a top and bottom plate secured together, said top plate having a pair of spaced openings disposed laterally from the central longitudinal line of the slider and on each side thereof, a pull tab pivotally connected to said top plate and having a pair of lugs adapted to enter the said openings and to press the attached ends of elements disposed beneath said openings, said bottom plate having a pair of depressions beneath said lugs terminating in end walls in the path of the attached ends of the elements depressed by said lug and a relatively elevated central longitudinal portion beneath the interlocking ends of the elements and intermediate the depressions, said central longi-

tudinal portion serving as a bearing on which the elements of each row are rocked as their attached ends are depressed by said lugs into the depressions whereby the interlocking ends of the elements are relatively undisturbed from their normal interlocking alignment while the attached ends of the elements depressed into the depressions are prevented from moving by the end walls of the latter.

5 10 6. A slider such as is defined in claim 5, in which the end walls of the depressions are in

staggered relation to each other and the bottom surfaces thereof incline upwardly from the lower edges of said walls to the interior surfaces of the bottom plate and said lugs are in staggered relation to each other, at least one of said lugs extending forwardly from the pivotal axis of said pull tab to such an extent that in the limited and locked position of said pull tab such lug will maintain said tab in locked position.
